UNITED STATES PATENT OFFICE.

SAMUEL M. LUTZ, OF KINGMAN, KANSAS.

GRAIN-LIFTING DEVICE.

1,287,057.

Specification of Letters Patent. Patented Dec. 10, 1918.

Application filed November 9, 1917. Serial No. 201,141.

To all whom it may concern:

Be it known that I, SAMUEL M. LUTZ, a citizen of the United States, residing at Kingman, in the county of Kingman, State 5 of Kansas, have invented certain new and useful Improvements in Grain-Lifting Devices; and I do hereby declare the following to be a full, clear, and exact description of the invention, such as will enable others 10 skilled in the art to which it appertains to make and use the same.

This invention relates to new and useful improvements in attachments for grain separators, and pertains more particularly 15 to devices for handling headed grain.

The primary object of the invention is to provide a device by means of which headed grain may be manipulated to be fed to a grain separator.

20 A further object of the invention is to provide a device of this character which is power operated, the device deriving its power from the machine on which it is used.

Figure 1 is an end view of a separator having my improved structure mounted thereon,

Fig. 2 is a horizontal sectional view,

Fig. 3 is an enlarged detail view of one of the boom supports,

Fig. 4 is another enlarged detail view of 30 the same portion of the mechanism,

Fig. 5 is a transverse section on line 5—5 of Fig. 1, and

Fig. 6 is a detail of one of the crane constructions.

35 Referring more particularly to the drawings, 1 represents the base of the mechanism which is mounted upon the platform of a grain separator in any desirable or suitable manner. Carried by the base 1, upon opposite sides of the machine, are the stanchions 2 which are provided with the enlarged heads 3 so as to provide comparatively widely extended top surfaces. The stanchions 2 are centrally and vertically recessed to provide step bearings for 45 booms 4. The booms are therefore rotatable in the stanchions 2 and at their upper ends are guyed by means of a transverse connecting rod 5, the angularly directed guy rods 6 and forward and rear guy rods 7. Each of the booms 4 carries a crane arm or 50 spar 8, whose foot is heeled upon a bearing collar 9 which surrounds the corresponding boom in fixed relation thereto above the 55 top surfaces of the heads 3. The outer

ends of the spars or crane arms 8 are connected to the heads of the booms 4 by means of cables 10 which are passed in adjustable relation through the blocks 11 which are carried by the booms and spars so that the 60 crane arms may be adjusted for height, or may be lowered on to the separator when the latter is packed for transport.

Furthermore, the collars 9 are annularly provided with worm gear teeth, which are 65 adapted to alternately mesh with the worms 12 and 13 which are fixed upon shafts 14 and 15 respectively. Said shafts 14 and 15 are journaled in slide plates 16 which rest upon the tops of the heads 3, and are yoked 70 around the collars 9 in such a manner as to have a certain degree of slidability. The worms 12 and 13 are mounted upon the shafts 14 and 15 respectively between the 75 bearings of the latter upon the plates 16, and therefore stand opposite the worm gears which are formed upon the collars 9, and owing to the slideable relation of the plates 16, may be alternately carried in the mesh with the worm gears. Thus, by means of 80 the manipulation of the plates 16, the booms may be rotated in one direction or the other in accordance with the worm 12 or 13 which is brought into mesh with the worm gear. In order to slide the plates 16, the latter are 85 connected by links 17 with hand levers 18 which are mounted upon the free ends of fixed arms 19 which project from the sides of the stanchions 2.

The shafts 14 and 15 are driven by means 90 of a counter-shaft 20 which is mounted upon the base 1 below the shafts 14 and 15 and is provided with a belt pulley 21 which is adapted to be connected to the most convenient part of the driving power of the threshing machine. The counter-shaft 20 is geared to the shaft 14 by means of a sprocket chain 22 which runs over sprockets 23 and 24 carried by the shafts 14 and 20, and the shaft 15 is also driven by means of a 100 sprocket wheel or chain 25 which connects the two shafts 14 and 15. Mounted upon the shaft 14 is a pair of drums 26 which are loosely carried thereon, but may be fixed thereto by means of the clutch members 27 which are adapted to be operated by means of 105 clutch levers 28. Cables 29 which are wound upon the drums 26 pass through pulleys 30 carried by a horizontal guy rod 31 and thence through pulleys 32 on the upper ends of the 110

booms 4, to pulleys 33 on the outer ends of the spars 8, from which the cables then suspend to carry the forks 34.

In the operation of the mechanism above described, grain may be rapidly and continuously fed to the threshing machine feeding table from stacks on both sides of the separator. Furthermore, the grain may be fed with a minimum of effort, since the lifting 10 is entirely done by mechanical means, and workmen are only required to feed the forks 34 and to control the action of the fork lifting drums and the rotation of the cranes. The drums 26 are controlled in an obvious 15 manner, while the rotation of the booms 4 is occasioned by carrying one or another of the worms 12 or 13 into engagement with the worm gears by sliding the plates 16 across the head 3. Since both of the shafts 20 14 and 15 are continuously driven by means of flexible drive chains, the slight movement which is necessary to carry the gears 12 and 13 into engagement with the worm gear does not interfere with the continuous motion of 25 the shafts, and the rotation of the booms 4 is effectively accomplished without the use of a complicated reversing gear.

What I claim as my invention is:—

1. A device of the class described including a base, a plurality of booms upstanding from the base, spars carried by said booms, a turning collar mounted on the lower portion of each boom, worm gear teeth on said collars, a pair of plates mounted on the base 30 adjacent the booms and slidable transversely of the booms, bearings on said plates, a pair of shafts extending longitudinally between the booms and journaled in the bearings and having their ends disposed at the sides of the turning collars, gear worms on the ends 35 of the shafts adapted to selectively mesh with the teeth of said collars, means for sliding the plates transversely of the booms to selectively engage the gear worms with the collar teeth, a drive connection between the shafts, a shaft disposed under one of the 40 turning collars and a drive connection between the shaft and the worm shaft permitting lateral movement of the worm shaft.

2. A device of the class described includ-

ing a base, a plurality of booms upstanding from the base, spars carried by said booms, a turning collar mounted on the lower portion 50 of each boom, worm gear teeth on said collars, a pair of plates mounted on the base adjacent the booms and slidable transversely of the booms, bearings on said plates, a pair of shafts extending longitudinally between the booms and journaled in the bearings and having their ends disposed at the sides of the turning collars, gear worms on the ends 55 of the shafts adapted to selectively mesh with the teeth of said collars, means for sliding the plates transversely of the booms to selectively engage the gear worms with the collar teeth, a drive connection between the shafts, a shaft disposed under one of the 60 turning collars and a drive connection between the shaft and the worm shaft permitting lateral movement of the worm shaft.

3. A device of the class described including a base, a plurality of booms upstanding from the base, spars carried by said booms, a 70 turning collar mounted on the lower portion of each boom, worm gear teeth on said collars, a pair of plates mounted on the base adjacent the booms and slidable transversely of the booms, bearings on said plates, a pair 75 of shafts extending longitudinally between the booms and journaled in the bearings and having their ends disposed at the sides of the turning collars, gear worms on the ends of the shafts adapted to selectively mesh with the teeth of said collars, means for sliding the plates transversely of the booms to selectively engage the gear worms with the collar teeth, means for driving the shafts, lifting drums loosely mounted on one of the 80 shafts, means for clutching said drums to the shaft and cables wound on said drums and connected with the spars.

In testimony whereof, I affix my signature in the presence of two witnesses.

SAMUEL M. LUTZ.
